Primary Examiner — Mary Ann Calabrese*Assistant Examiner* — Catherine Ho(74) *Attorney, Agent, or Firm* — Michael Best & Friedrich LLP(57) **CLAIM**

We claim the ornamental design for an edge power unit, as shown and described.

DESCRIPTION

FIG. 1 is a perspective view of an edge power unit, showing our new design

FIG. 2 is a top view thereof;

FIG. 3 is a bottom view thereof;

FIG. 4 is a first side view thereof;

FIG. 5 is a second side view thereof;

FIG. 6 is a first end view thereof; and,

FIG. 7 is a second end view.

The broken line portion of the figure drawings is included to show portions of the article that form no part of the claimed design.
